(57) **CLAIM**

The ornamental design for a crawl space door and frame with exterior flange, as shown and described.

DESCRIPTION

FIG. 1 is a front plan view of a crawl space door and frame with exterior flange showing our new design;

FIG. 2 is a front and side perspective view thereof;

FIG. 3 is a front and side perspective view of a crawl space frame with exterior flange shown separately for clarity of illustration;

FIG. 4 is a top elevation view of the frame shown in FIG. 3 it being understood that the bottom elevation view is a mirror image thereof; and,

FIG. 5 is a side elevation view of the frame shown in FIG. 3 it being understood that the opposite side elevation view is a mirror image thereof.
